UNITED STATES PATENT OFFICE.

ELLA DOLBEAR LEE, OF CHICAGO, ILLINOIS.

DOLL.

1,075,482.

Specification of Letters Patent.

Patented Oct. 14, 1913.

Application filed January 3, 1913. Serial No. 740,060.

To all whom it may concern:

Be it known that I, ELLA DOLBEAR LEE, a citizen of the United States, residing at Chicago, in the county of Cook and State of Illinois, have invented a new and useful Doll, of which the following is a specification.

The present invention relates to improvements in dolls, and more particularly to a doll formed from a flat material such as paper or other flexible fabric, the primary object of the present invention being the provision of a cut-out doll provided with front and back sections, each one of which carries a single leg, so that the doll may be supported in an upright standing position when properly assembled.

A further object of the present invention is the provision of a cut-out doll, the head of which is provided with a movable section whereby the eyes may be caused to assume either an open or closed position to simulate a wide-awake or sleeping doll.

A still further object of the invention is the provision of a cut-out doll, in which the front section constitutes the complete front of the doll and one leg, and the rear portion is composed of two separable pieces constituting the lower half of the doll with a single, or the other leg, said legs being so positioned as to when desired form a support to sustain the doll in an upright position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a front elevation of the front blank. Fig. 2 is an elevation of the rear blank. Fig. 3 is a detachable front portion of the leg carried by the rear blank. Fig. 4 is an edge view of the completed doll. Fig. 5 is a front elevation of a modified form of blank. Fig. 6 is an elevation of the upper section of the rear blank. Fig. 7 is a similar view of the lower section of the rear blank and constituting the separable supporting medium. Fig. 8 is a detachable blank for forming the front portion of the leg carried by the rear

section. Fig. 9 is a vertical sectional view through the various blanks constituting the completed doll made with the sections shown in Figs. 5, 6, 7 and 8. Fig. 10 is a detail view of the pivoted member carried by the head to simulate a wide-awake or sleeping doll. Figs. 11 and 12 are plan views illustrating front and rear respectively of a hair ribbon and eye carrying flaps.

Referring more particularly to Figs. 1, 2, 3 and 4, the numeral 1 designates the front body section, which as shown is provided with a single projection constituting in the present instance the right leg of the doll. 60 The foot in the present instance is indicated as pointing directly forward and constitutes as shown in Fig. 4 the front support for assisting and holding the completed doll in a vertical or standing position. The rear blank 3 is provided with the leg forming portion 4, whose foot portion 5 is extended to assume a position at right angles to the foot portion of the leg 2, and constituting in the present instance the left leg of the doll, 65 70 75 80 85 90 95 100 105 110

the same when positioned to support the doll, being substantially in the rear of the right leg 2 and in such a position as to assist in preventing the doll from falling rearwardly or sidewise. These blanks are connected so that the head, the arms and the portion of the body down to the point as indicated at 8 in Figs. 1, 2 and 4 are co-extensive or secured together by means of an adhesive. In order to provide a finished effect upon the front surface of the leg 4, the leg blank 6 as a separable piece is provided and is connected to the front face of the leg blank 4 by means of an adhesive. In the form shown in Figs. 5, 6, 7, 8, 9 and 10, the front body blank 9 is somewhat similar to the blank shown in Fig. 1, except that it is provided with the rivet apertures 10 adjacent the waist line, eye openings 11 in the head thereof, and the aperture 12 for the pivoting means, as will presently appear. The back blank in the present instance is composed of two members, the lower or straight member 13 being provided with a projecting waist band portion 14 having the apertures 15 which are disposed to register with the apertures 10 of the front body blank 9 for the reception of the fastening means or rivets 16, as clearly shown in Fig. 9. The upper rear body member, as 17, is provided with the apertures 18 which when the body portion 17 is adhesively connected

to the rear of the body portion of the blank 9, such apertures 18 will register with the apertures 10 and 15 respectively so that the fastening means 16 will pierce all three sections, as clearly shown in Fig. 9, and thus secure these members in such relation that the respective legs carried by the sections 9 and 13 may be extended to form a support for the doll, and in a similar manner to that 5 shown in Fig. 4. The section or member 17 is cut away at the head portion as at 19 for the introduction of the pivoted plate 21, which is secured between the head section of the members 9 and 17 by means of the pivoting pin 20 to be incased, as shown in Fig. 10, so that as the plate 21 is manipulated through the means of the handle portion 22 accessible through the recessed portion 19, the dots 23 simulating the eye ball of the 15 doll or the portions 24 simulating the closed lids thereof will be presented through the eye holes or openings 7 of the member 9. Although this pivoted plate 21 is shown only used in connection with the form of doll 20 shown in Figs. 5 through 9, it is apparent that the same may be applied to the head of the doll as illustrated in Figs. 1 through 4 by simply notching the head portion of the member 3 and forming a pocket or recess 25 therein in conjunction with the head portion of the member 1, as clearly shown in Fig. 9.

Although the back as shown in Figs. 6 and 7, is composed of two members, if it is desirable to dispense with the back portion 17 35 (Fig. 6,) the rear of Fig. 5, having printed thereon, the representation of the back of the head and waist garment, as shown in Fig. 6, the section 13 of Fig. 7, being readily attached as described to Fig. 5. When this 40 is done, the eye and ribbon carrying flap Figs. 11 and 12, are employed, the ribbon side being disposed exteriorly of the rear of the head in Fig. 5, with the other face disposed to simulate a sleeping or wide awake 45 doll.

From the foregoing description, it is evident that with a doll constructed according to the present invention, that the legs are so positioned and carried by the 50 respective front and rear blanks thereof, as to assume the necessary spaced positions to support the doll against forward or rearward and sidewise movements and in the desired standing or upright position. This 55 may be accomplished as shown either by the two membered doll as shown in Figs. 1 through 4, or the three membered doll as shown in the other figures, any means being provided for fastening the sections together 60 so that the sections may be separated from the waist line down to provide the desired necessary supporting means as herein illustrated.

What is claimed is:

65 1. A doll made from a plurality of blanks

connected at a point adjacent the waist line so as to provide two movable spaced surface engaging and supporting projections simulating the legs of the doll, one projection being formed with a laterally projecting portion to prevent sidewise tilting movement while both, when separated, coact to prevent forward and rearward tilting movement. 70

2. A doll made from a plurality of blanks 75 connected together at a point intermediate the ends thereof, each of said blanks having formed and projecting from the lower edge thereof a portion simulating a leg, the foot of one of the legs being extended outwardly 80 to provide a longer supporting base than the foot of the other leg, and said legs being disposed for separation to form spaced supports for the doll. 85

3. A doll made from a plurality of blanks, 90 each of said blanks having formed and projecting from the lower edge thereof a portion simulating a leg, the foot of one of the legs being extended outwardly to provide a longer supporting base than the 95 foot of the other leg, said blanks being connected together down to a point adjacent the waist line so that the portion below the waist and the legs may be moved to and from each other to change the relative position of the feet. 100

4. A doll, having two blanks forming the front and rear portions of the head, arms and body, and a single leg, said blanks being attached together at the waist line to permit the leg portions to be moved to and from each other to form a spaced support for the doll and the foot portion of one leg being of greater length than the foot portion of the other leg. 105

5. A doll, having two blanks forming the front and rear portions of the head, arms and body and a single leg, said blanks being attached together at the waist line to permit the leg portions to be moved to and from each other to form a spaced support for the doll, the foot portion of one of the blanks being of greater length than the foot portion of the other blank to provide a longer supporting base and to prevent sidewise 110 tilting movement of the doll when in upright position. 115

6. A doll made from three separate blanks, two of the blanks being formed so that each one has a body portion and one 120 leg, while the third blank constitutes the opposite side of one of the legs, the first two blanks being connected together to permit the legs to be moved to form spaced supports to hold the doll in an upright or 125 standing position. 130

7. A doll made from three separate blanks, two of the blanks being formed so that each one has a body portion and one leg, while the third blank constitutes the 130

opposite side of one of the legs, the blanks having the body portions being secured together at their waist line so that the lower portions of the body and both legs may be
5 swung in spaced relation to each other to form a bracing support for the doll when in an upright or standing position.

In testimony that I claim the foregoing as my own, I have hereto affixed my signature in the presence of two witnesses.

ELLA DOLBEAR LEE.
